CONTAINER VACUUMIZING AND CLOSING MACHINE

Howard B. Peterson, San Francisco, and Roland E. Renard, San Jose, Calif., assignors to American Can Company, New York, N. Y., a corporation of New Jersey

Original application January 14, 1942, Serial No. 426,760. Divided and this application November 25, 1944, Serial No. 565,136

4 Claims. (Cl. 226—82)

1

The present invention relates to a vacuum closing machine for sealing containers or cans and has particular reference to vacuum devices for controlling the operation of a knockout element used in the machine. This is a division of our United States application Serial Number 426,760 filed January 14, 1942 for Closing Machine, issued April 9, 1946 as Patent No. 2,397,979.

An object of the invention is the provision, in a can closing machine of a knockout pad located in a can sealing head and which is controlled by a vacuum condition within a can sealing chamber forming a part of the machine so that the can cover will be held in place on the can during the operations incident to closing the can.

Numerous other objects and advantages of the invention will be apparent as it is better understood from the following description, which, taken in connection with the accompanying drawings, discloses a preferred embodiment thereof.

Referring to the drawings:

Figure 1 is a vertical section taken through the can sealing chamber portion of a can closing machine embodying the instant invention; and

Figs. 2, 3 and 4 are fragmentary enlarged sectional views of the closing head knockout and its associated parts used in the machine and a can and cover to be united to seal the can, the views illustrating the different positions of the moving parts in relation to the can and the cover during the operations incident to closing the can.

As a preferred embodiment of the instant invention the drawings illustrate an improved knockout device for a vacuum can closing machine. In a closing machine, filled sheet metal cans A are vacuumized and are then closed with covers or end members B which are secured in place on the cans by an interlocking of flange parts to produce uniting seams of the well-known double seam character.

A can A to be vacuumized and closed is placed, in any suitable manner, within a sealing chamber 21 (Fig. 1) partially enclosed by walls of a frame 22 which constitutes the main frame of the machine. In the instant machine the remainder of the sealing chamber is enclosed by a door 23 which is hingedly secured to the machine frame although the invention is equally well adapted to other types of machines in which cans are passed into the chamber through valves or other means. The chamber and the can therein are vacuumized from any suitable source of vacuum

through an opening or hole 24 formed in the chamber enclosing walls of the frame 22. The usual cut-off valve in the vacuum line (not shown) connecting with the hole 24 is utilized to control the exhausting of the air from the chamber and the breaking of the vacuum at the proper time.

The can while in the sealing chamber 21 is supported on a lifter pad or support 25 which is mounted on the upper end of a vertically movable rod 26 carried in a long bearing block 27 secured in a bearing 28 formed in the frame 23 adjacent the lower end of the sealing chamber. The rod is moved or reciprocated vertically in any suitable manner.

The cover B to be secured to the can is placed in superimposed position above the can, within a horizontal ring or support 31 which is located within the sealing chamber 21. The ring is disposed above the can in spaced relation thereto so that the top of the can will be free of the cover during vacuumization of the chamber and the can.

While the can A and the chamber 21 are in a vacuumized condition, the can is raised by the lifter pad 25 to meet the cover B and then both can and cover are further lifted into a continuously rotating sealing head 36 (Fig. 1) for the can sealing operation hereinbefore mentioned. The sealing is effected preferably by seaming rollers 37 which are carried on the head in the manner usual in such sealing heads.

The hinged door 23 and the sealing head 36 may be of the character shown and described respectively at 25 and 55 in United States Patent 2,113,591, issued April 12, 1938 to S. S. Jacobs, on Vacuum Closing Machine. The sealing head 36 is mounted in the sealing chamber 21 and is carried on a hollow vertical shaft 41 journaled in a bearing 42 and in a casing 43 mounted on top of the machine frame 22. The shaft rotates on a sleeve 44 which is carried in a bearing 45 spaced above the shaft bearing 42. The sleeve guides a knockout stem 48 which extends down through the sealing head and carries on its lower end a knockout pad or element 49.

The sealing head 36 is rotated continuously through a differential drive as by a pair of spur gears 51, 52 which are mounted on the head shaft 41 and on the rotatable sleeve 44 within the shaft. This is a usual sealing head drive. These gears mesh with and are driven by a pair of driving gears 53, 54 which are mounted on a vertical drive shaft 55 journaled in bearings 56, 57 formed in the casing 43. The upper end of the

drive shaft carries a grooved pulley 58 which is rotated in any suitable manner as by means of a belt 59.

Referring now to the knockout stem 48 it will be observed that the upper end of this stem extends up into a hollow casing 62 (see also Figs. 2, 3 and 4) enclosing a compartment or chamber 63 covered on its top by a flexible vacuum cup or diaphragm 64. The cup is secured to the top end of the knockout stem and is backed up by a compression spring 65 surrounding the stem inside the casing. Compartment 63 constitutes a variable pressure chamber which is constantly in communication with the sealing chamber 21 by way of a tube 66 which connects these parts. The outer surface of the vacuum cup or diaphragm 64 is subjected at all times to outside atmospheric pressure which enters the casing 43 through holes or apertures 67 in a wall of the casing.

Thus when an atmospheric pressure condition exists within the sealing chamber 21, as when the chamber door 23 is open, or has just been closed (Fig. 1), or just prior to opening, air enters the compartment 63 of the knockout device through tube 66 and thus balances the pressure on the vacuum cup or diaphragm 64. This permits the compression spring 65 to force the cup and the knockout stem 48 upwardly and thus hold the knockout pad 49 in a normal position within the sealing head 36, as best shown in Fig. 1.

When the sealing chamber 21 has become vacuumized, by operation of the described usual control valve in the vacuum line leading from the hole 24, the air is exhausted from the knockout compartment 63 by way of the tube 66 and this unbalances the pressure on the vacuum cup 64. Atmospheric pressure acting on the outer surface of the cup at such a time compresses the spring 65 and thus lowers the knockout stem 48. This brings the knockout pad 49 down into engagement with the can cover B in the ring 31 as shown in Fig. 2 and thus holds the cover under pressure until the rising can A picks it up.

During the upward travel of the can and the cover, the can through the cover lifts the knockout pad 49, against the atmospheric pressure on the vacuum cup or diaphragm 64. This action takes place while the pressure on the can cover is maintained and this keeps it seated on the can. When the can and cover enter the sealing head 36 and as long as they remain in the head, the vacuum within the compartment 63 permits exterior air pressure acting against the vacuum cup 64 to hold the knockout pad tight against the can cover, as shown in Fig. 3.

At the completion of a can sealing operation as the sealed can is moved by the lifter pad 25 down into its original position, the atmospheric pressure acting on the outer surface of the vacuum cup 64 still holds the knockout pad 49 in contact with the can cover. This pushes the sealed can down until it is below and clear of the cover support ring 31. Fig. 4 shows the can further lowered from the pad.

When the vacuum is broken within the sealing chamber 21, by operation of the described valve in the vacuum line as hereinbefore mentioned, such a condition is relayed to the compartment 63 by way of the tube 66. The spring 65 thereupon lifts the knockout pad 49 into its normal uppermost position within the head 36 (Figs. 1 and 3). In this normal position, the pad is clear of the cover support ring 31 and will not inter-

fere with the opening of the door 23 to remove the sealed can. In this manner and by these devices the operation or vertical reciprocation of the knockout pad 49 is controlled by the vacuum condition in the sealing chamber 21 throughout the entire can vacuumizing and sealing cycle of the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for vacuumizing and sealing containers, the combination of a sealing chamber, means for vacuumizing said chamber, a container sealing head within said chamber, a support also within said chamber for holding a container and a superimposed cover in sealing position in said head, a movable knockout member having an actuating stem in said head for holding the cover on the container and for ejecting the sealed container from the head, a casing surrounding said stem enclosing a compartment adjacent the stem, means for communicably connecting said compartment with said can sealing chamber for transmitting the air pressure condition of said chamber to said compartment, and a flexible diaphragm constituting a wall of said casing enclosing said compartment, said diaphragm being secured to said knockout stem and having its outer surface exposed to atmospheric conditions, said diaphragm actuating said stem and its attached knockout member in accordance with air pressure conditions within said sealing chamber, for moving said knockout member into and out of operating engagement with said container cover.

2. In a machine for vacuumizing and sealing containers, the combination of a sealing chamber, means for vacuumizing said chamber, a container sealing head within said chamber, a support also within said chamber for holding a container and a superimposed cover in sealing position in said head, a movable knockout element having an actuating stem in said head for holding the cover on the container and for ejecting the sealed container from the head, a casing surrounding said stem enclosing a compartment adjacent the stem, a tube communicably connecting said compartment with said can sealing chamber for creating the same air pressure conditions in said chamber and in said compartment, a flexible diaphragm constituting a wall of said casing enclosing said compartment, said diaphragm being secured to said knockout element stem and exposed on its outer surface to atmospheric conditions, said diaphragm actuating said stem and its attached knockout element in accordance with air pressure conditions within said sealing chamber for moving said knockout element into and out of operating engagement with said container cover, and a compression spring in said compartment engaging said diaphragm and exerting counter pressure against atmospheric pressure on the diaphragm for reciprocating said knockout element towards and away from the container cover for the purposes described.

3. A machine for vacuumizing and sealing containers, comprising a sealing chamber hav-

ing means connected thereto for drawing a vacuum therein, a sealing head within said chamber, a variable pressure chamber communicably connected to and responsive to pressure conditions in said sealing chamber, a movable support disposed within said sealing chamber for holding a container and its superimposed cover in sealing position in said head, movable knockout means in said head extending into said pressure chamber for holding the cover on the container and for ejecting the sealed container from the head, and means responsive to air pressure outside of said sealing chamber for moving said knockout means into operating engagement with said container cover.

4. A machine for vacuumizing and sealing containers, comprising a sealing chamber having means connected thereto for drawing a vacuum therein, a container sealing head within said chamber, a variable pressure chamber communicably connected to and responsive to pressure conditions in said sealing chamber, a movable support disposed within said sealing chamber for holding a container and its superimposed cover in sealing position in said head, 25 movable knockout means in said head extending

into said pressure chamber for holding the cover on the container and for ejecting the sealed container from the head, means normally holding said knockout means within said sealing head, and means in said pressure chamber connected to said knockout means and responsive to atmospheric pressure outside of said sealing chamber for moving said knockout means relative to the sealing head into operating engagement with said container cover.
